UNITED STATES PATENT OFFICE.

JOHN HUSS, OF MIDDLETOWN, PENNSYLVANIA.

SCYTHE.

No. 908,995

Specification of Letters Patent.

Patented Jan. 5, 1908.

Application filed August 25, 1908. Serial No. 450,130.

To all whom it may concern:

Be it known that I, JOHN HUSS, citizen of the United States, residing at Middletown, in the county of Dauphin and State of Pennsylvania, have invented certain new and useful Improvements in Scythes; and I do hereby declare the following to be a full, clear, and exact description of the invention, such as will enable others skilled in the art to 10 which it appertains to make and use the same.

This invention relates to new and useful improvements in scythes and has relation more particularly to an attachment therefor.

It is an object of the invention to provide a 15 cradle for scythes which can be readily applied to a scythe of any well known construction.

It is also an object of the invention to provide a novel attachment of this character which 20 can be readily adjusted with relation to the scythe.

It is also an object of the invention to provide a novel device of this character which will be simple in construction, efficient and 25 advantageous in practice and comparatively inexpensive to manufacture.

With the above and other objects in view, the invention consists in the detail of construction, and in the novel arrangement and 30 combination of parts to be hereinafter referred to.

In describing the invention in detail, reference will be had to the accompanying drawings forming a part of the specification, 35 wherein like characters of reference denote corresponding parts in the several views and in which:

Figure 1 is a view in perspective of the scythe with the attachment applied thereto 40 and Fig. 2 is a view in end elevation of the cradle detached, the supporting rod therefor being omitted.

In the drawings, 1 denotes a snathe of the scythe, having the usual hand grasps 2, and 3 45 denotes the blade of the snathe.

The attachment of cradle, comprises two posts 4, through which pass the fingers 5, said fingers being straight and projecting beyond the forward post 4, the projecting portions of the fingers being pointed and varying, 50 in length in succession, from the blade 3. The ends of the posts are adapted to abut the

flange of the blade. In order that said contact of the posts with the flange may be secure, said ends of the posts 4 are notched as at 6, the flange of the blade 3, extending within the notches as is believed to be apparent.

The blade 3 has secured thereto at 7, the hook 8, which projects over and beyond the flange of the blade 3, said hook engages the strap 9 which is arranged around certain of the fingers 5, as shown in Fig. 1. By this arrangement it is thought to be obvious that the cradle is securely held to the blade 3. In order to further support the cradle, and to hold it against accidental displacement, the outer end of the inner post 4 is perforated as at 9^a, and extending within this perforation 9^a, is the angular end 10 of a rod 11. This rod passes upward on an incline and intersects or crosses the snathe 1 and is held thereto through the medium of a rawhide thong 12. It is thought to be within the province of the invention to state that in lieu of this rawhide thong, any other suitable means may be employed. The rod 11 permits an adjustment of the cradle with relation to the blade, as the requirements of practice may necessitate.

In employing an attachment of the kind described, it is not necessary to swing around to the left in order to empty the cradle, but only mow along as usual as the rod 11, or brace as it may be called, will hold the grain until the scythe stops moving to the left, when the grain will topple over, forming an even swath. This feature is very important as it makes mowing a great deal easier than the well known method now in use.

I claim:

1. In combination with the blade of a scythe, a cradle attachment therefor comprising posts and fingers, said posts contacting with the blade, a hook carried by the blade and a strap secured to the fingers of the cradle attachment, said strap being engaged by the hook.

2. In a scythe of the class described the combination with a blade and a snathe to which said blade is secured; of an attachment comprising posts having notches in their lower ends to engage the blade and fingers extending through said posts, a hook on the

blade, a strap surrounding portions of said fingers and engaged by the hook, a rod engaging the upper end of one of the posts and extending into engagement with the snathe
5 and means to adjustably secure the rod to the snathe.

In testimony whereof I have signed my

name to this specification in the presence of two subscribing witnesses.

JOHN HUSS.
